(57) **CLAIM**

The ornamental design for a coffee brewing system, substantially as shown and described.

DESCRIPTION

FIG. 1 is a perspective view of the preferred embodiment of the coffee brewing system of the present invention; FIG. 2 is a front elevation view of the coffee brewing system of FIG. 1;

FIG. 3 is a left side elevation view of the coffee brewing system of FIG. 1;

FIG. 4 is a right side elevation view of the coffee brewing system of FIG. 1;

FIG. 5 is a back elevation view of the coffee brewing system of FIG. 1

FIG. 6 is a top view of the coffee brewing system of FIG. 1; and,

FIG. 7 is a bottom view of the coffee brewing system of FIG. 1.
